UNITED STATES PATENT OFFICE.

FRANCIS W. BOST, OF CHINA GROVE, NORTH CAROLINA.

CIRCUIT-CLOSER FOR FIRE-ALARMS.

1,153,755.

Specification of Letters Patent. Patented Sept. 14, 1915.

Application filed August 29, 1914. Serial No. 859,236.

To all whom it may concern:

Be it known that I, FRANCIS W. Bost, a citizen of the United States, residing at China Grove, in the county of Rowan and State of North Carolina, have invented a new and useful Circuit-Closer for Fire-Alarms; and I do hereby declare the following to be a full, clear, and exact description of the invention, such as will enable others skilled in the art to which it appertains to make and use the same.

This invention relates to a circuit closer for fire alarm systems, which is adapted for use in connection with the electrically operated annunciator as shown in the patent to F. W. Bost and B. Gobel, of October 3, 1911, Patent No. 1,004,846.

An object of the invention is the provision of a circuit closer having simple, efficient and practical features of construction.

In practical fields the details of construction may necessitate alterations, falling within the scope of what is claimed.

The invention comprises further features and combination of parts, as hereinafter set forth, shown in the drawings and claimed.

In the drawings:—Figure 1 is a view of the improved circuit closer shown in use in connection with an annunciator. Fig. 2 is a sectional view longitudinally through the circuit closer. Fig. 3 is a detail perspective view of the circuit closer showing the hood or cover removed. Fig. 4 is a transverse sectional view on line 4—4 of Fig. 3.

Referring more particularly to the drawings, 1 designates a metallic plate, elongated, and trough-shaped in cross section, and provided with laterally extending ears 2, for the reception of screws 3, whereby the circuit closer may be attached at any suitable location in a building. One end of the elongated plate is provided with screw threaded apertures 4, for the reception of screws 6, which pass through the insulating members 7, and also through the metallic sheet metal plate 8, which is provided with a binding screw or terminal 9, for connecting a lead or wire 11. Soldered or otherwise connected to the sheet metal plate 8 is a spring blade

tongue 12 having a stiffening member 13, soldered or otherwise fixed on one face of the blade. This spring blade tongue is to be constructed of such metal sufficiently sensitive to cause the blade to expand toward the binding screw or terminal 15, that is, owing to the intensity of the heat. A wire or lead 16 is connected to the binding screw 15, which wire or lead in turn has suitable connections with the annunciator. The binding screw or terminal 15 is threaded in the overhanging split arm 18 of the elongated plate 1. The casting or plate 1 adjacent said lug or arm is provided with an opening, to permit the flame or the heat to pass therethrough and act upon the tongue or blade, to cause the same to expand toward the said screw.

On each side of the plate or casting 1 adjacent each end are indentures 19, to receive the projections 20 of the hood or cover 21. Said projections are formed by indenting the sides of said hood or cover. By these projections and indentures the cover or hood is held securely in place.

The invention having been set forth, what is claimed as new and useful is:—

In a circuit closer, an elongated plate being grooved upon its under surface and having an elongated opening at one end, the end having said opening having an arm integral therewith rising upwardly and having a split portion overlying said opening, a lead terminal carried by said arm adjacent where the same is integral with the plate, a pair of insulating members secured to the other end of said plate, an expansible blade tongue consisting of two sections, one secured between said insulating member and provided with a lead terminal, the other section being connected to the section between the insulating members and provided with a stiffening device, and an element threaded between the parts of the split portion of the arm to coöperate with the stiffened section of the tongue and being adjustable whereby the tongue will act under different temperatures, said plate having ears extending laterally from its longitudi-

nal side, and a skeleton cover plate arching over the insulating members, the expandible tongue, and the split portion of the arm and having ears on its longitudinal side registering with the first ears, including means for connecting the ears to hold the first plate and the cover plate together.

In testimony whereof I have signed my name to this specification in the presence of two subscribing witnesses.

FRANCIS W. BOST.
